UNITED STATES PATENT OFFICE.

WILLIAM HENRY SMITH AND FRANK WILLIAM GUNTON, OF LONDON, ENGLAND.

AUTOMATIC MUSICAL INSTRUMENT.

1,075,509.

Specification of Letters Patent.

Patented Oct. 14, 1913.

Application filed December 7, 1908. Serial No. 466,223.

To all whom it may concern:

Be it known that we, WILLIAM HENRY SMITH, a subject of the King of England, residing at Penge, London, S. E., England, and FRANK WILLIAM GUNTON, a subject of the King of England, residing at London, W., England, have invented certain new and useful Improvements in Automatic Musical Instruments, of which the following is a specification:

This invention relates to improvements in automatic musical instruments and is applicable either to automatic players for pipe or reed organs or to piano-players or to combined players (i. e. automatic piano-players having organ attachments.) Dealing with piano-players the invention is applicable either to "inside pneumatic" instruments or "outside pneumatic" instruments, that is to say either to those in which the power-pneumatics are disposed within a vacuum chamber as in the well known Angelus instrument or to those in which the power-pneumatics are outside the vacuum chamber as in many common forms of piano-player. The invention will first be described in its application to an outside-pneumatic piano-player. The expression "vacuum" will be used to indicate a pressure less than that of the atmosphere and it will be understood that air pressure may be used instead of vacuum, allowance being made for the reversal of movement thus involved.

The object of this invention is to provide means for automatically playing or accenting certain notes in the music such as the melody in accordance with certain perforations in the music sheet. Owing to the limited width of music rolls it is essential that the minimum number of holes should be employed in the tracker-board and an important aim in the invention is to accomplish the desired accentuation by the aid of as few as possible extra holes in the tracker-board. It is already known in automatic piano-players to employ two sources of vacuum, one normal and the other excessive, and to provide means for connecting the power-pneumatics of certain notes as desired to one or other of these sources and the present invention involves this general idea. It is also known to control accentuation of all the notes of one name or all the notes of one octave by the use of one orifice at the tracker-board.

According to this invention in an automatic apparatus for playing a musical instrument the method of controlling a conduit for playing or accenting a note involves the employment of a flexible diaphragm which covers both said conduit and a special tracker-conduit for accenting a note and the raising of which flexible diaphragm is dependent on the special tracker-conduit and a group controlling-pneumatic, and therefore necessitates the simultaneous opening of two special tracker-conduits belonging to different groups. Thus a pressure controlling pneumatic (which puts the ordinary secondary pneumatic-valve into connection either with normal vacuum or with excessive vacuum) is controlled by a pressure controlling pneumatic-conduit, a flexible diaphragm covers this pressure controlling conduit and covers also a special conduit from the tracker-board (which I shall term the diaphragm-actuating-conduit) appropriated to a certain class of note (say the notes of one name); and a diaphragm-controlling pneumatic actuated from the tracker-board and appropriated to a certain group of notes, say an octave, is arranged to control the atmosphere surrounding the flexible diaphragm whereby the pressure controlling pneumatic is only operated as to an individual note when the corresponding diaphragm-actuating-conduit and the diaphragm-controlling pneumatic-conduit for the group containing said note are simultaneously opened at the tracker-board. For convenience the one pressure controlling pneumatic may control two consecutive notes (separated by a semi-tone) because as is well known, two consecutive notes practically never occur in one chord. It will be seen that when a secondary-pneumatic is actuated from the music sheet in the usual way, the corresponding power-pneumatic is normally actuated by normal vacuum. The power-pneumatic cannot be actuated by excess vacuum unless the pressure controlling pneumatic is operated and the pressure controlling pneumatic cannot be operated unless the flexible diaphragm is raised and this only occurs when the diaphragm-actuating-conduit is opened at the tracker-board and the diaphragm-controlling-pneumatic-conduit is also and simultaneously open at the tracker-board. By this means according to this invention it is possible by the use of certain extra holes on the music sheet to select cer-

tain notes (say the melody) and to cause the corresponding power-pneumatics to be operated by the excess vacuum.

In the accompanying drawings:—Figure 5 1 is a diagram representing one method of applying this invention to an “outside pneumatic” piano player and Fig. 2 is a diagrammatic view illustrating the power pneumatics grouped in pairs and connected 10 to the tracker board and other selecting and group-controlling diaphragms which are in turn connected to the tracker board.

Referring to Fig. 1, the power-pneumatic A for each note has a conduit B as usual to the secondary-pneumatic valve C which in normal position leaves the power-pneumatic open to air at C¹, but in raised position puts the power-pneumatic into connection with the discharge D¹ from the pressure 20 controlling pneumatic-valve D. The secondary-pneumatic C is controlled from the primary-pneumatic and from the tracker-board in the usual way, and of course instead of the primary and secondary pneumatics, single pneumatics may be used. In 25 the drawing the passage C² leading to the secondary pneumatic is diagrammatically represented as controlled by a valve. The pressure controlling pneumatic-valve D controls two ports one E¹ from the normal 30 vacuum chamber E and another F¹ from the excess vacuum chamber F. In its normal lower position the pressure controlling pneumatic-valve D closes the excess vacuum 35 port F¹ and opens the normal vacuum port E¹, but in its raised position the pressure controlling pneumatic-valve D closes the normal vacuum port E¹ and opens the excess 40 vacuum port F¹. This pneumatic is controlled through the selecting pneumatic conduit D². The end of this conduit is 45 covered by a flexible diaphragm G say of leather which also covers another conduit H (the diaphragm-actuating-conduit) leading from the diaphragm G to the tracker-board. The diaphragm-actuating-conduits H from 50 all the actions of the notes of one class (say all the notes of the same name) lead into one common conduit from the tracker-board, so that one hole in the tracker-board controls the diaphragm G for all the notes of that class. The diaphragm G itself is in a chamber J (the diaphragm chamber) which is 55 normally open to the air at K¹. As there is normally a vacuum in the pressure controlling pneumatic-conduit D² and as the diaphragm-actuating-conduit H is closed, and as there is normally air pressure in the diaphragm chamber J on the other side 60 of the diaphragm, it follows that the diaphragm G normally closes both the pneumatic-conduit D² and the diaphragm-actuating conduit H. The atmosphere in the diaphragm chamber J is controlled by a 65 group-controlling-pneumatic-valve K hav-

ing two ports one K¹ to the air and the other K² to vacuum. When the group-controlling-pneumatic-valve K is in its normal lower position the diaphragm chamber J is open to the air but when the group-controlling-pneumatic-valve K is in its raised position, the diaphragm chamber J is opened to vacuum. There is one group-controlling-pneumatic K for each group of flexible diaphragms, say every six of them, viz. to control an octave. Each group-controlling-pneumatic K is connected by a conduit K³ to the tracker-board. Bleed-holes L leading from the vacuum space to the underside of all the pneumatics are provided as usual. Assuming for example that a certain selecting pneumatic D controls two consecutive notes C and C sharp, assuming that the conduit H from the tracker-board is connected to the flexible diaphragms for all the C's, and assuming that each of the group-controlling-pneumatics K controls an octave of notes, the operation of this arrangement is as follows:—If it be desired to accent the particular note C referred to, the usual orifice is made in the music sheet corresponding to the primary-pneumatic of that note, an orifice is provided in the music sheet opposite the diaphragm-actuating-conduit H for the C's, and an orifice is 95 provided in the music sheet opposite the group-controlling-pneumatic conduit K³ for the particular octave in which the note occurs. The group-controlling-pneumatic valve K is therefore raised, vacuum is 100 created above the flexible diaphragm G, and the air is admitted from the music orifice to the diaphragm-actuating conduit H for the C's, passes under the diaphragm G and enters the pressure controlling pneumatic conduit D². By this means the pressure controlling pneumatic valve D is raised and the excess vacuum port F¹ is therefore 105 opened to the secondary pneumatic C which is of course raised in the usual way by the air in the conduit C² and the excess vacuum therefore takes effect upon the power-pneumatic A.

In the above example certain groupings of the notes have been referred to but it will be 115 understood that this invention is equally applicable to other groupings of the notes.

The so-called normal vacuum and excess vacuum may both be conveniently derived from the one vacuum reservoir through the 120 medium of choker valves or other suitable form of valve. Preferably the choker valve devices controlling the passages between the vacuum reservoir and the normal and excess vacuum chambers are of the type covered in 125 the previous United States Patent.

When a whole chord or a group of notes is to be accented it may not be desired to actuate all the selecting pneumatics, flexible diaphragms, and group-controlling-pneu-

matics for all the notes in that chord or group and in such circumstances automatic means may be provided actuated by an additional hole or holes in the music sheet to cause all the secondary pneumatics to be put into connection with the excess vacuum chamber. This may for example be effected by means of a choker-valve in a well known way.

10 It is to be understood that the details of arrangement and construction may be varied without departing from this invention.

What we claim as our invention and desire to secure by Letters Patent is:—

15 1. In an automatic apparatus for playing a musical instrument, the combination with a tracker, sources of normal and excess pressure, pneumatics for each note operated through said pressures, conduits from said 20 tracker to said pneumatics, of a pressure controlling pneumatic, a conduit therefrom terminating in a diaphragm chamber, a tracker conduit terminating in said chamber, a flexible diaphragm covering both conduits 25 and actuated through said tracker conduit, and a pneumatic for controlling a group of diaphragms operated from the tracker and arranged to condition said diaphragm for operation through said tracker conduit.

30 2. In an automatic apparatus for playing a musical instrument, the combination with a tracker, sources of normal and excess pressure, pneumatics for each note operated through said pressures, conduits from said

35 tracker to said pneumatics, of a pressure controlling pneumatic, a conduit therefrom terminating in a diaphragm chamber having an air inlet and a vacuum inlet, a tracker conduit terminating in said chamber, a flexible diaphragm in said chamber covering both of said conduits, and a pneumatic for controlling a group of diaphragms operated from the tracker and arranged to close said inlets alternately and to condition 40 said diaphragm for operation through said tracker conduit whereby said pressure controlling pneumatic may be operated.

3. In an automatic apparatus for playing a musical instrument, the combination with a tracker, sources of normal and excess pressure, pneumatics for each note operated through said pressures, and conduits from said tracker to said pneumatics, of a plurality of pressure controlling pneumatics, a plurality of diaphragm chambers, conduits from said pressure controlling pneumatics terminating in said chambers, a plurality of tracker conduits terminating in said chambers, a flexible diaphragm in each chamber, 55 each diaphragm covering a pressure controlling conduit and a tracker conduit, and a pneumatic for controlling a group of diaphragms operated from the tracker and arranged to condition a diaphragm for operation through its tracker conduit.

4. In an automatic apparatus for playing musical instruments, the combination of a series of pressure controlling pneumatic conduits (one for each note) grouped into sets, a diaphragm chamber for each set, said conduits of each set terminating in said chamber, a tracker conduit appropriated to each of said pressure controlling conduits of each set, said tracker conduits terminating in said diaphragm chamber, a plurality of flexible diaphragms in said chambers, each diaphragm covering a pressure controlling conduit and a tracker conduit, and a pneumatic for controlling a group of diaphragms in each diaphragm chamber arranged to determine the air pressure therein.

5. In an automatic apparatus for playing musical instruments, the combination of a series of pressure controlling conduits (one for each note) grouped into sets, a diaphragm chamber for each set, a tracker conduit appropriated to each pressure controlling conduit, the tracker conduits of each set terminating in the diaphragm chamber for said set, said pressure controlling conduits terminating in their diaphragm chambers, a plurality of flexible diaphragms in each diaphragm chamber, each diaphragm covering a pressure controlling conduit and a tracker conduit, a plurality of pneumatics each controlling a group of diaphragms in each diaphragm chamber, and a pneumatic conduit for each of said pneumatics leading to the tracker.

6. In an automatic apparatus for playing a musical instrument, the combination with a tracker, sources of normal and excess pressure, pneumatics for each note operated through said pressures, and conduits leading from said tracker to said pneumatics, of a pressure controlling conduits such as D^2 for accenting notes, and a flexible diaphragm such as G controlling these notes, of diaphragm chambers such as J containing a plurality of diaphragms, each chamber being controlled by one group-controlling pneumatic operated from the tracker, such as K , and tracker conduits such as H appropriated to said diaphragms and grouped together substantially as described.

7. In an automatic apparatus for playing musical instruments, the combination with a tracker, sources of normal and excess pressure, pneumatics for each note operated through said pressures and conduits from said tracker to said pneumatics, of a pressure controlling pneumatic conduit D^2 leading to a diaphragm chamber J having an air inlet K' and a vacuum inlet K^2 , a diaphragm-actuating conduit H , a tracker conduit appropriated thereto, a flexible diaphragm G within said diaphragm chamber which covers both said conduits, and a pneumatic K for controlling a group of diaphragms arranged to close alternately the

air inlet and vacuum inlet of said diaphragm chamber.

8. In an automatic apparatus for playing musical instruments, the combination with a tracker, sources of normal and excess pressure, pneumatics for each note operated through said pressures and conduits from said tracker to said pneumatics, of a pressure controlling pneumatic, a conduit therefrom, a tracker conduit, a flexible diaphragm valve covering both the conduit to the pressure controlling pneumatic and said tracker conduit, and a pneumatic for controlling a group of diaphragm valves actuated from the tracker and appropriated to a certain group of notes (say an octave),

said pneumatic being arranged to control the atmosphere surrounding the diaphragm, whereby the selecting pneumatic is only operated when the corresponding tracker conduit to said diaphragm and said group-controlling pneumatic conduits are simultaneously opened at the tracker. 20

In testimony whereof we have signed our names to this specification in the presence 25 of two subscribing witnesses.
